UNITED STATES PATENT OFFICE

ALFRED L. BOEGEHOOLD, OF DETROIT, MICHIGAN, ASSIGNOR TO GENERAL MOTORS RESEARCH CORPORATION, OF DETROIT, MICHIGAN, A CORPORATION OF DELAWARE

SHOCK ABSORBER

Application filed March 26, 1927. Serial No. 178,672.

This invention relates to shock absorbers or snubbers for vehicles, to cushion rebound after spring deflection and improve the riding qualities of the car.

The invention contemplates an improved type of shock absorber, in which a retracting spring or the like, resists the violent reaction or tendency of the vehicle body to bounce upward after the vehicle spring has been compressed. The past objection to this type of snubber, lies in the fact that when the vehicle spring is under maximum tension, the retracting or snubber spring is under minimum tension, and it does not reach its peak of resistance until the vehicle spring has returned to its normal position of minimum tension. Since the initial maximum expansive force of the vehicle spring on the rebound, acts against the minimum contractive force of the snubber spring, only a small resistance is at first offered thereto, and only as the reaction proceeds to completion does it meet with the increased resistance of the snubber spring. Thus the return of the parts is not smooth and easy, and it is only during the latter portion of the rebound that there is present a cushioning effect of any consequence. The relation of the two opposing forces being at such wide variance, it will be seen that the action of the snubber spring is not uniform or equal throughout the range of movement.

To meet the situation, it is proposed to employ a rotating cam member in association with the retracting spring, which upon rotation presents a variable mechanical advantage that is utilized to control the application of spring tension, to offer the proper degree of resistance throughout the relative movement of the frame and axle. The arrangement is such that the respective spring forces are brought into closer relation with each other, the retractive force of the snubber spring being always of slightly less value than the expansive force of the vehicle spring.

A preferred embodiment of the invention is illustrated in the accompanying drawing, wherein:

Figure 1 is a fragmentary view, showing a portion of a front axle supporting a chassis

frame member, and the application of the present shock absorber.

Figure 2 is a vertical sectional view thru the casing for the operating parts, showing their relative positions.

Figure 3 is a view on line 3—3 of Figure 2.

Referring more particularly to the drawing, the reference character 1 indicates a channel shaped longitudinally extending side member of a vehicle chassis frame, which is flexibly supported by a multiple leaf, load bearing spring 2, upon the road axle 3. The load bearing spring may be of any suitable character, that shown in the drawing being a semi-elliptical spring, pivotally connected at its ends to the frame member 1, by swinging shackle links as at 4.

Secured directly above the axle 3 to the frame member 1, by bolts 4' or the like, is a housing or casing 5, formed with integral bosses or lugs 6 and 7, projecting inwardly from the inner side wall thereof, which bosses may be apertured and interiorly screw threaded for engagement therein of studs or pins 8 and 9, which extend thru apertured bosses 10 and 11 on the outer wall of the casing.

The pin 8 in this instance, has mounted thereon a rotary drum or roller 12, and a helical coiled retracting spring 13 is shown surrounding the pin, having one extremity turned radially inward as at 14, into engagement with an opening in the pin, while its other end 15, is bent laterally and extends into the hub of the rotary drum 12. The other pin 9, serves as a fulcrum for the elliptical cam or eccentric member 16, revolvably mounted thereon. One end of a flexible strap 17 is riveted or otherwise attached for winding upon the spring retracted drum 12, and the intermediate portion of the strap passes upwardly over the periphery of the cam member 16, being fixedly secured at the major axis of the cam, as by means of a screw 18. The opposite end of the strap 17, extends downwardly and out thru an opening in the bottom of the housing, and is fastened to the top of the axle 2 by the screw stud 19.

In Figure 2, the full line position of the parts indicates their normal relation, as when the vehicle is at rest and the load support-

ing springs expanded to their full extent. Here the retracting spring 13 is under its maximum tension. Its force, however is exerted upon the short axis of the cam, the mechanical advantage of the cam favoring the load supporting spring. The broken line 5 position of the parts in this same figure, illustrates the axle and frame members drawn close together, as when the load supporting 10 spring is compressed by travel over uneven roadways. In this case, the spring 13 is retracted, after having rotated the drum 12 to take up slack in the strap, by winding the strap on the drum, and correspondingly 15 turning the cam 16. The pull of the spring 13, which is at minimum tension, acts directly on the long leverage or major axis of the cam, so that the effort of the retracting spring is multiplied thru the cam, to 20 offset the maximum expansive tension of the supporting spring. The tension of the respective springs to be employed, is taken into account and the cam is so shaped or proportioned that the pull upward on the axle is at 25 all times a few pounds less than the expansive tendency of the vehicle spring, whereby the restoration of the parts is smoothly accomplished and the body of the car is prevented from being thrown upward by the reaction 30 or sudden rebound.

From the above description, it will be apparent that relative movement of the axle and frame permits an automatic adjustment of the rotary cam thruout the entire range 35 of movement, giving a uniform interaction between opposing spring forces at all times.

While the device has been more or less specifically described it is to be understood that it is not limited to the exact details shown, 40 but that such modifications may be made as come within the scope of the appended claims.

Having described my invention I claim:

1. In combination with a vehicle frame, an axle and a load supporting spring interposed 45 between the axle and frame, of a shock absorber comprising a spring element carried by the frame, a connection between the spring element and the axle through which the spring element exerts its tension in opposition to said load supporting spring, and means associated with intermediate portion 50 of said connection, adapted to afford a variable mechanical advantage to both springs, inversely with respect each other to automatically maintain the effort of opposing 55 springs in substantially the same relation thruout the range of movement of the axle and frame.

2. In combination with a vehicle frame, an 60 axle and a load supporting spring interposed between the axle and frame of a retractile spring element carried by the frame and a rotatable cam having a fixed axis with respect to said spring element and a flexible strap passing around and having an in- 65

termidiate portion fixedly attached to the cam and having its opposite ends secured respectively to the spring element and axle, the relative movement of the axle and frame, thru said strap, retracting and expanding 70 said spring element and rotating the cam to automatically vary the leverage afforded thereby inversely as the value of the spring tension varies.

3. The combination with an expansible 75 spring, a contractile spring, and a strap secured at opposite ends to the respective springs, thru which said springs exert their influence in opposition to each other, of a rotary cam element having a connection with 80 an intermediate portion of said strap, the cam surface to one side of said connection affording a bearing surface for a portion of the strap to provide a variable leverage effect on the action of one spring and the cam 85 surface on the other side of said connection affording a bearing surface for another portion of the strap to provide a variable leverage effect on the action of the other spring.

4. The combination with an expansible 90 spring, a contractile spring, and a strap secured at opposite ends to the respective springs, through which said springs exert their influence in opposition to each other, of an eccentrically pivoted member over which 95 the strap passes and to which an intermediate portion of the strap is connected adjacent the major axis of the eccentric member, the rotation of said member in one direction affording increased leverage in favor 100 of the contractile spring as said spring contracts and the rotation of said member in the opposite direction affording increased leverage in favor of the expansible spring as said spring expands.

5. The combination with an expansible 105 spring, a contractile spring, and a strap secured at opposite ends to the respective springs, through which said springs exert their influence in opposition to each other, 110 of an eccentrically pivoted member over which the strap passes and to which an intermediate portion of the strap is connected adjacent the major axis of the eccentric member, said strap being adapted to progressively 115 bear upon the receding surfaces of said member on opposite sides of said major axis, as the member moves toward one or the other of its opposite limits, whereby the mechanical advantage of said member favors one or the 120 other of said springs depending upon the direction of rotation thereof.

6. A shock absorber for vehicles having a chassis frame supported by a vehicle spring on an axle, including a retractile element carried by the frame, a rotary cam member interposed between the axle and said retractile element, a flexible strap fixed at opposite ends to the retractile element and axle respectively, and passing over and secured to 125 130

the cam element adjacent the major axis thereof, whereby upon relative movement of the frame and axle, said cam element will be caused to rotate and affect the opposing forces of said vehicle spring and retracting spring by presenting a variable leverage effect on both of said forces.

In testimony whereof I affix my signature.
